UNITED STATES PATENT OFFICE.

GEORGE WILLIAM DE TUNZELMANN, OF LONDON, ENGLAND.

DESIGN FOR AN ELECTRIC-LAMP SHADE.

SPECIFICATION forming part of Design No. 32,203, dated February 6, 1900.

Application filed June 19, 1899. Serial No. 721,177. Term of patent 7 years.

To all whom it may concern:

Be it known that I, GEORGE WILLIAM DE TUNZELMANN, a subject of Her Majesty the Queen of Great Britain, residing at London, county of Middlesex, England, have invented and produced a new and original Design for Electric-Lamp Shades, of which the following is a specification, reference being had to the accompanying drawings, forming part thereof.

Figure 1 is a sectional side elevation showing my new design. Fig. 2 is a plan view of same.

As shown in the drawings, the leading or material feature of my design consists of a

hollow circular chamber *a*, having a concave *b* upper surface *b* and convex lower surface *c* and a central aperture *d*.

It is apparent that this design is also applicable to lamp-shades other than electric.

Having described my invention, what I claim as new, and desire to secure by Letters Patent, is—

The design for a lamp-shade as herein shown and described.

GEORGE WILLIAM DE TUNZELMANN.
